United States Patent Office.

JOHN CORREJA, OF BROOKLYN, NEW YORK.

Letters Patent No. 71,365, dated November 26, 1867.

IMPROVED SASH-CORD FASTENER.

The Schedule referred to in these Letters Patent and making part of the same.

TO ALL WHOM IT MAY CONCERN:

Be it known that I, JOHN CORREJA, of Brooklyn, in the county of Kings, and State of New York, have invented, made, and applied to use, a certain new and useful Improvements in Sash-Cord Fasteners; and I do hereby declare the following to be a full, clear, and exact description of the said invention, reference being had to the annexed drawing, making part of this specification, wherein—

Figure 1 is an elevation of said cord-fastener, and

Figure 2 is a vertical section of the same.

Similar marks of reference denote the same parts.

Heretofore it has been usual to plough a groove in the edge of the window-sash, and from that bore a hole into a larger hole entering the edge of the sash, so as to thread the sash-cord into place, and tie a knot that remains in this last-named larger hole. This is attended with considerable labor, both in making the sash and hanging it, and if the sash has to be planed off, the groove and hole are not deep enough in the wood. To remedy these difficulties, an iron ring has been made to set into the edge of the sash, with a lip, behind which the cord at the knot is passed, but in practice this is found to cut the sash-cord, and also to allow the knot to project and rub the window-frame as the sash goes up or down.

The nature of my said invention consists in a metallic socket for the knot, closed, or nearly so, on its outer end, so as to keep the knot from contact with the window-frame, in combination with a tubular cord-holder formed on one side of the knot-socket, and through which the cord passes, in such a manner that there is no liability of the cord being cut near the knot.

In the drawing, *a* represents a portion of the sash-frame with the groove *b* on its edge for the cord *d*. *c* is a socket for the knot of the cord *d*, and *e* is the tubular cord-holder passing off on the upper side of the socket *c*. Through this the cord passes, and is protected from cutting or injury near the knot, and the cord-holder *e* passes into the groove *b*, while the knot-holding socket *c* is entered into a hole bored into the edge of the sash. As an additional security, the socket *c* may be continued down in the form of a flange, *f*, and receive a screw so that the cord-fastener cannot become loosened or project from the side of the sash. This metallic socket becomes a fixture to the sash-cord itself, and allows the sash to be disconnected from the cord by simply drawing said socket out of its cavity in the side of the sash. This allows the sash to be removed with great facility for planing off the edges if it becomes necessary in easing the sash, or for cleaning and polishing the glass, and the sash-cord cannot be drawn into the weight-box when detached from the sash, because the metallic socket becomes a stop against the pulley.

What I claim, and desire to secure by Letters Patent, is—

The sash-cord fastener, formed of the socket *c*, for enclosing the knot, combined with the tubular cord-holder *e* upon one side, and adapted to being applied to the sash, in the manner specified.

In witness whereof I have hereunto set my signature this eighth day of August, A. D. 1867.

JOHN CORREJA.
